UNITED STATES PATENT OFFICE

2,093,994

SEPARATOR

Hjalmar T. Blom, Michigan City, Ind., assignor
to Sullivan Machinery Company, a corporation
of Massachusetts

Application August 5, 1935, Serial No. 34,712

14 Claims. (Cl. 183—92)

My invention relates to separating devices, and, more particularly, to separating devices for the separation of moisture from air lines, steam lines, and the like.

It is highly desirable that air compressors raising the pressure of air through a substantial pressure range should separate out the moisture from the compressed air, and after-cooling devices are accordingly frequently provided, with a result that much of the entrained moisture may be condensed or formed into a mist such that by appropriate treatment it may be separated from the air.

It is an object of my invention to provide an improved separating device. It is another object of my invention to provide an improved separating device for separating moisture from flowing air. It is a further object of my invention to provide an improved separating device applicable to substantially any problem of separating liquid from a flowing stream of gases or vapors. It is a further object of my invention to provide an improved separating device which will effectually remove moisture from air leaving an after-cooler. Other objects and advantages of the invention will hereinafter more fully appear.

In the accompanying drawing, in which for purposes of illustration one embodiment which the invention may assume in practice has been shown,

Fig. 1 is a side elevation of a separating device.

Fig. 2 is a section on a plane corresponding to the line 2—2 of Fig. 1.

Fig. 3 is a horizontal section on planes corresponding to the lines 3—3 of Fig. 2.

Fig. 4 is a transverse section on the plane of the line 4—4 of Fig. 2 through a nozzle device.

Fig. 5 is a transverse section on the plane of the line 5—5 of Fig. 2.

In the drawing, 1 represents a delivery pipe, as, for example, the delivery pipe from an after-cooler, through which a mixture of a gas or vapor and a liquid, either in drop or mist form, enters the separator device 2. The separator device 40 comprises a shell 3, herein cylindrical in cross section and provided with a discharge opening 4, herein formed in the side wall thereof and near one end thereof, said discharge opening provided with a suitable connection 5 whereby an attachment may be made, as at 6, to a discharge line 7. In the illustrative embodiment of the invention the separator is arranged in an upright position, and the discharge opening is near the upper end thereof. The bottom of the shell 3 is closed by 55 a plate 8 supported by a rim 9, and the top of

the casing is provided with an annular member 10, herein welded thereto and supporting a baffle-chamber-forming member 11 which extends downwardly within the chamber 12 of the shell 3. The baffle-chamber-forming member 11 is 5 provided with a bottom 14 and is generally circular in cross section and is suitably supported, as by welding, to the member 10. Within the interior 15 of the member 11 there are arranged a series of upright baffle devices 16, each in the 10 form of a thin strip secured, as by welding, to the interior of the member 11. Discharge orifices 17 open through the side wall of the member 11 near the lower end thereof. Member 11 is preferably eccentric to casing 3. 15

An upper plate or cover plate 18, to which the connection 1 is suitably secured, as at 19, is held in any suitable manner, as by bolts 20, to the member 10 and carries within the chamber 15 a nozzle device 21 which is designed to impart a 20 whirling motion to the entering material. The nozzle device 21 comprises an inwardly extending frusto-conical hollow portion 22 whose bottom is reversely directed, as at 23, so as to provide a 25 generally conical inward projection and so promote a uniform distribution of the entering material circumferentially of the member 21. The apex 24 of the inwardly directed distributing cone 23 is in alignment with an opening 25 in the member 18 and with the delivery connection 30 30. The peripheral wall of the member 21 is provided with a series of spirally extending, expanding passages 26 which are designed to impart a 35 whirling motion to the entering material. The member 21 is so proportioned as to provide as high velocity as possible without an excessive drop of pressure.

The direction of the whirling action imparted by the device 21, the disposition of the baffle elements 16 and the location of the discharge orifices 17 bear a definite optimum relation to each other. For example, assuming that the whirling motion imparted by the nozzle passages 26 is clockwise, looking down upon the apparatus, the baffle devices 16, instead of being at right angles to tangents to the whirling body of material within the chamber 15, should be inclined slightly against the travel of this material; and the discharge orifices 17 should each lie behind a baffle 16. Through the bottom 14 of the device 11 there 50 is provided, moreover, forwardly of each baffle 16, a discharge opening 27 through which the separated material, e. g., liquid, may pass into the bottom of the chamber 12, from which it escapes 55 through a further connection 28. The baffle de-

vices do not extend as high within the chamber 15 as the bottom of the nozzle device 21.

The mode of operation of the illustrative embodiment shown and described will now be obvious. Material, for example, water-bearing air, will enter, through the connection 1 and the opening 25, the interior of the nozzle device 21 and will there be smoothly and evenly distributed to the various passages 26, which will impart a 10 whirling motion at a high velocity to the entering material. Due to the space above the tops of the baffles 16 this whirling motion may be thoroughly established before the baffles are encountered, and the liquid carried with the air stream 15 will have opportunity, due to its greater weight and the effect of centrifugal force, to reach the periphery of the chamber 15 before the baffles are encountered. As the contents of the chamber 15 encounter the baffles, the liquid will be separated 20 from the air by the baffles and will flow down along the forward sides of the latter to the discharge openings 27, any tendency to be carried off of the baffles by the continued whirling of the air being overcome by a forward inclination 25 of the baffle strips. The whirling air will escape through the orifices 17 behind the baffle strips, these orifices being located in such a manner as to insure their receiving a minimum of air which has not engaged a baffle. As the air passes 30 out through the openings 17, it will enter a passage whose size increases from a point opposite opening 4 towards said opening, and in this passage it encounters the inner wall of the shell 3 as well as the outer wall of 16 and has to flow from 35 near the lower end of the shell up to the upper end of the latter, and the wall friction and the reversal of direction of flow will further tend to separate out remaining moisture from the air. The liquid discharged through the openings 27 40 and that which is separated out in the space 12 between the outside of the device 11 and the inner wall of the shell 3 and flows down along the inner wall of the shell, will pass out through the discharge connection 28.

45 It will be evident from the description given that I have provided a simple, inexpensive, efficient and very durable separating device, that it can be made with a minimum of machining operation, and that it takes advantage of the 50 cumulative effects of centrifugal force, baffling, and wall friction for separating entrained moisture from the air.

55 While there is in this application specifically described one form which the invention may assume in practice, it will be understood that this form of the same is shown for purposes of illustration and that the invention may be modified and embodied in various other forms without departing from its spirit or the scope of the appended claims.

60 What I claim as new and desire to secure by Letters Patent is:

1. In a separator, a shell having a discharge opening therefrom, a chamber-forming member 65 within said shell, a nozzle device within said chamber-forming member having an inlet opening and providing means for imparting a whirling motion to material emerging from said nozzle, baffle means in said chamber-forming member disposed for impingement by material in such 70 whirling motion, means for establishing communication between the interior of said chamber-forming member and the space between said chamber-forming member and said shell, and 75 discharge means for separated material.

2. In a separator, a shell having a discharge opening therefrom at one end thereof, a chamber-forming member within said shell, a nozzle device within said chamber-forming member having an inlet opening and disposed at the end 5 of said chamber-forming member nearer the discharge opening from the shell, baffle means in said chamber-forming member, means for establishing communication between the interior of said chamber-forming member and the space between 10 said chamber-forming member and said shell, said communication-establishing means arranged at that end of said chamber-forming member remote from said nozzle device, and discharge means for separated material. 15

3. In a separator, a shell having a discharge opening therefrom arranged in the side thereof, a chamber-forming member within said shell disposed eccentrically within the latter, a nozzle device within said chamber-forming member 20 having an inlet opening, baffle means in said chamber-forming member, means for establishing a communication between the interior of said chamber-forming member and the space between said chamber-forming member and said shell including an opening in the wall of said chamber-forming member at the side of the latter remote from the discharge opening in the shell, and discharge means for separated material. 25

4. In a separator, a shell having a discharge opening therefrom, a chamber-forming member within said shell, a nozzle device within said chamber-forming member having an inlet opening and having provision for effecting a whirling 30 of the material passing therethrough about the axis of the chamber-forming member, baffle means in said chamber-forming member extending parallel to the axis of the chamber in said chamber-forming member in position for impingement by material whirled by said nozzle device, means for establishing communication between the interior of said chamber-forming member and the space between said chamber-forming member and said shell, and discharge 35 means for separated material. 40

5. In a separator, a shell having a discharge opening therefrom, a chamber-forming member within said shell, a nozzle device within said chamber-forming member having an inlet opening and having provision for effecting a whirling 50 of the material passing therethrough about the axis of the chamber-forming member, baffle means in said chamber-forming member extending parallel to the axis of the chamber in said chamber-forming member, means for establishing communication between the interior of said chamber-forming member and the space between said chamber-forming member and said shell, said communication-establishing means arranged 55 behind, with reference to the direction of material circulation in the chamber, said baffle-forming means, and discharge means for separated material. 60

6. In a separator, a shell having a discharge 65 opening therefrom, a chamber-forming member within said shell, a nozzle device within said chamber-forming member having an inlet opening and having provision for effecting a whirling motion of the material passing therethrough, baffle means in said chamber-forming member including baffle strips extending longitudinally 70 of the chamber-forming member and disposed for impingement by whirling material, means for establishing communication between the interior of said chamber-forming member and the space 75

between said chamber-forming member and said shell, and discharge means for separated material including openings in said chamber-forming member at the ends of said baffle strips.

5 7. In a separator, a shell having a discharge opening therefrom, a chamber-forming member within said shell, a nozzle device within said chamber-forming member having an inlet opening and having provision for effecting a whirling motion of the material passing therethrough, baffle means in said chamber-forming member including baffle strips extending longitudinally of the chamber-forming member and terminating short of said nozzle device, means for establishing communication between the interior of said chamber-forming member and the space between said chamber-forming member and said shell, and discharge means for separated material including openings in said chamber-forming member at the ends of said baffle strips.

10 8. In a separator, a shell having a discharge opening therefrom, a chamber-forming member within said shell, a nozzle device within said chamber-forming member having an inlet opening and having provision for effecting a whirling motion of the material passing therethrough, baffle means in said chamber-forming member including baffle strips extending longitudinally of the chamber-forming member and terminating short of said nozzle device, means for establishing communication between the interior of said chamber-forming member and the space between said chamber-forming member and said shell, and discharge means for separated material including openings in said chamber-forming member at the ends of said baffle strips at the sides of the latter first reached by the whirling chamber contents.

15 9. In a separator device, an outer shell having a discharge opening near one end thereof, a longitudinally extending baffle-chamber-forming device eccentrically disposed in said shell whereby the maximum space between the walls of said device and said shell is adjacent said discharge opening, a spiral-flow-producing nozzle member arranged in the end of said baffle-chamber-forming device nearer said discharge opening, baffles within said device extending longitudinally thereof, openings for the escape from said device of separated material arranged at the forward sides of said baffles, discharge orifices opening through the walls of said device behind said baffles, and a discharge orifice for the separated material opening from the interior 20 of said shell at the end thereof remote from said discharge opening.

25 10. In a separator, a shell having a discharge opening therefrom, a chamber-forming member within said shell, a nozzle within said chamber-forming member having an inlet opening and providing passages for effecting a whirling of material entering said chamber-forming member about the axis of the latter, baffle means in said chamber-forming member projecting inwardly from the wall thereof and extending generally longitudinally thereof, means for establishing communication between the interior of said chamber-forming member and the space

between said chamber-forming member and said shell including openings partially shielded by said baffle means as the material whirls in said chamber-forming member, and discharge means for separated material.

30 11. In a separator, a shell having a discharge opening therefrom, a chamber-forming member within said shell, a nozzle device having an inlet opening and arranged to deliver material with a whirling motion into the interior of said chamber-forming member, baffle means in said chamber-forming member projecting inwardly from the inner wall of the latter, and means for establishing communication between the interior of said chamber-forming member and the space between the latter and said shell and for discharging separated material from said chamber-forming member respectively arranged at opposite sides, in terms of direction of material travel in said chamber-forming member, of said baffle means.

35 12. In a separator, a shell having a discharge opening therefrom arranged in the side thereof, a chamber-forming member within said shell disposed eccentrically within the latter, a nozzle device within said chamber-forming member having an inlet opening, baffle means in said chamber-forming member, discharge means for separated material, and means for establishing communication between the interior of said chamber-forming member and the space between the latter and said shell including openings arranged symmetrically around the periphery of said chamber-forming member and including an opening at the side of said chamber-forming member remote from the discharge opening in the shell.

40 13. In a separator, a shell having a discharge opening therefrom, a chamber-forming member within said shell, a nozzle device within said chamber-forming member having an inlet opening and also having provision for effecting a whirling of material passing therethrough about the axis of the chamber-forming member, inwardly projecting baffle means in said chamber-forming member extending generally longitudinally of the latter along the inner wall thereof, means for establishing communication between the interior of the chamber-forming member and the space between the latter and the shell, and discharge means for separated material at the side of said baffle means first reached by whirling material in said chamber-forming member.

45 14. In a separator, a shell having a discharge opening therefrom, a chamber-forming member within said shell, a nozzle device within said chamber-forming member having an inlet opening, baffle means in said chamber-forming member disposed in a longitudinally different transverse zone of said chamber-forming member from said nozzle device, means for establishing communication between the interior of said chamber-forming member and the space between said chamber-forming member and said shell, and discharge means for separated material.

HJALMAR T. BLOM.
